UNITED STATES PATENT OFFICE.

OSCAR L. LAWSON AND JAMES H. REED, OF LYNN, MASSACHUSETTS.

LOOPER MECHANISM FOR LEATHER-SEWING MACHINES.

1,252,352.

Specification of Letters Patent. Patented Jan. 1, 1913.

Application filed March 27, 1915. Serial No. 17,530.

To all whom it may concern:

Be it known that we, OSCAR L. LAWSON, a subject of the King of Sweden, and JAMES H. REED, a citizen of the United States, residing at Lynn, county of Essex, State of Massachusetts, have invented a certain new and useful Improvement in Looper Mechanism for Leather-Sewing Machines, of which the following is a specification, reference being had therein to the accompanying drawings.

Our invention has for its object improvements in shoe sewing machines of the type shown in Patent No. 1,194,512 to Oscar L. Lawson, dated Aug. 15, 1916, and relates particularly to the mechanism by means of which the under thread is placed in the hook of the needle before it is drawn up through the work to form the loop through which 20 the shuttle thread is passed.

The present invention provides means for placing the thread in the needle accurately even when the machine is run at very high speed. This is accomplished by means of 25 a looper having an eye therein, and a hook coöperating therewith. The parts have such movement relatively to each other and to the needle that the back of the hook does not strike against the thread as it comes into 30 position ready to perform its work and therefore has no tendency to displace the thread or fray or break it. The mechanism by which this is accomplished is very simple.

The invention will be fully understood by 35 reference to the following description taken in connection with the accompanying drawings and the novel features thereof will be pointed out and clearly defined in the claims at the close of the specification.

40 Referring to the drawings, Figure 1 is a side elevation of stitch forming instrumentalities embodying our invention.

Fig. 2 is a front elevation of the looper, hook and needle, showing the formation of 45 the horizontal line of thread which is placed in the hook of the needle.

Fig. 3 is a front elevation showing the position of the looper and hook just before the hook contacts with the thread.

50 Fig. 4 is a side elevation showing the parts in the same position as in Fig. 2.

Fig. 5 shows the parts in the position occupied by the looper after it has been oscillated to place the thread in the hook of the 55 needle.

Fig. 6 is a plan view of these parts showing them in the same position as in Fig. 5.

Fig. 7 is a detail of the connection between the end of the fork 38 and the looper 60 shaft 18.

In the drawings, and particularly in Fig. 1 there is shown at 11 the shuttle, at 12 the hook needle, at 13 the presser foot and at 14 the work support, and at 15 the awl, these parts being in general the same as 65 those shown in said patent.

The under thread is placed in the hook of the needle 12 after it has passed down through the work by the coöperation of a looper 16 having an eye or thread guiding 70 portion therein through which the thread passes, and a hook 17. The looper 16 comprises a shaft 18 bent near the top at right angles. The looper shaft 18 is slidable in two lugs 19 and 20 in or secured to a fixed 75 part A of the machine. This upward sliding movement of the looper and hook is for the purpose of getting these members out of the path of the awl 15 when not employed in placing the thread in the hook of the 80 needle 12 and also to bring them and the under thread into position to lay the thread in the hook of the needle. While this movement is in an inclined plane, it is conveniently referred to as an upward movement 85 because its main object is to move the said parts to and away from the underside of the work support.

The upward movement of the looper and hook is produced by rotation of the cam 21 90 mounted on the cam shaft 22, said cam having a cam groove 23 in its face. In this cam groove is a follower 24 mounted on cam lever 25 pivoted at 26 to the frame of the machine. To the lower end of the looper 95 shaft 18 is secured a block 27 having two projections 28 and 29 (see Fig. 2) between which is a space of suitable shape to engage a disk or ball 30 formed on the end of the cam lever 25. The looper shaft 18 is 100 free to rotate in the block 27 but is adapted to be moved vertically by it by means of a plate 31 engaging a circular groove 32 in the looper shaft. It will therefore be seen that although the looper is free to be rotated 105 about its longitudinal axis it is given a longitudinal reciprocation by the rotation of the cam 21.

The hook 17 is pivoted at 33 to the block 27 carried by the looper shaft. A link 34 110

which is pivoted at one end at 35 to the frame A of the machine is pivoted at its other end at 36 to the hook 17. It will therefore be seen that as the looper 16 is slid 5 longitudinally by the rotation of the cam 21 the link 34 will swing the point or tip of the hook toward or away from the eye or thread guiding portion of the looper in a practically horizontal line. This will clearly 10 be seen from an examination of Fig. 2 where the looper and hook are shown in their highest vertical position, and the tip of the hook has been moved away from the eye of the looper. This movement pulls the thread out 15 to form a horizontal portion *a* which is adapted to be laid in the hook of the needle. To lay the portion *a* of the thread in the hook of the needle, the eye or thread guiding portion of the looper is moved 20 forward in an arc formed about the axis of the looper shaft as a center, the eye or thread guiding portion of the looper being offset and at a distance from the longitudinal axis of the looper. The path of 25 movement of the eye of the looper is shown by a dot and dash line in Fig. 6. This oscillation of the looper is accomplished in the following manner:—

In the cam 21 is formed a cam groove 36 30 in which is located a cam follower 37 mounted on a fork 38 which spans the shaft 22. The fork is therefore reciprocated in a horizontal plane by the rotation of the cam. The end of the fork 38 is secured to a member 39. (See particularly Figs. 2 and 7.) Said member 39 is pivotally connected by a pin 40 to a block 41 in which the looper shaft 18 is slidably mounted. Beneath the block 41 is a projection or lug 43 by which 40 the block is supported and prevented from sliding lengthwise of the looper shaft.

The block 41 and the looper shaft 18 are connected by means of a feather and groove 42, so that while the looper shaft is slidable 45 vertically it will be oscillated by the in and out movement of the fork 38.

The operation of the device is as follows—

The needle 12 passes through the hole in the work formed by the awl. About this 50 time, the looper and hook are in the position shown in Figs. 1 and 3. The hook and looper then rise, the hook being moved laterally to the position shown in Fig. 2 as it rises, forming a horizontal portion *a* of the 55 thread. Thereafter the looper is oscillated about its vertical axis to the position

shown in Fig. 6 by the cam groove 36, and connecting members. This movement carries the thread forward and lays it in the hook of the needle. The needle then rises 60 carrying the thread with it through the work and the hook and looper descend out of the path of the awl.

What we claim is:

1. A looper mechanism for a hook needle 65 sewing machine comprising a looper and hook movable longitudinally toward the position of the needle and pivoted together, and a link connected at one end to one of said members and at the other to a fixed 70 part of the machine and adapted to cause the longitudinal movement of said members to move the point of one of said members relatively to the other in a direction transverse to the line of movement of said members toward the needle. 75

2. A looper mechanism for a hook needle sewing machine comprising a looper and hook slidable longitudinally toward the position of the needle, one of said members 80 having a thread guiding portion offset from the longitudinal axis of the member, means for moving one of said members laterally of the line of movement of said members toward the needle, and means for moving 85 the offset member about its longitudinal axis in an arcuate path to lay the thread in the hook of the needle.

3. A looper mechanism for a hook needle sewing machine comprising a looper and 90 hook pivoted together and movable longitudinally toward the position of the needle, means for moving one of said members laterally of the line of movement of said members toward the needle whereby the thread 95 is pulled out to form a transverse portion which is adapted to be laid in the hook of the needle, one of said members having a thread guiding portion offset from the longitudinal axis of the member, and means for 100 moving the offset member about its longitudinal axis in an arcuate path after the thread is drawn out to lay the thread in the hook of the needle.

In testimony whereof we affix our signatures, in presence of two witnesses. 105
